Primary Examiner—Melvin B. Feifer*Assistant Examiner*—Cheri Cohen*Attorney, Agent, or Firm*—Louis T. Isaf; James A. Witherspoon[57] CLAIM

The ornamental design for a training carpet for use in sports, as shown and described.

DESCRIPTION

FIG. 1 is a perspective view of a training carpet for use in sports showing my new design;

FIG. 2 is a top plan view thereof;

FIG. 3 is a bottom plan view thereof;

FIG. 4 is a left elevational view thereof, the side opposite being a mirror image;

FIG. 5 is a front elevational view thereof;

FIG. 6 is a rear elevational view thereof; and,

FIG. 7 is a top plan view of a second embodiment of a training carpet for use in sports, wherein the narrowly-spaced, parallel lines indicate contrasting colors.
